UNITED STATES PATENT OFFICE.

WALTER J. BELL, OF LOS ANGELES, CALIFORNIA, ASSIGNOR OF ONE-HALF
TO LEON F. MOSS, OF LOS ANGELES, CALIFORNIA.

WING FOR FLYING-MACHINES.

SPECIFICATION forming part of Letters Patent No. 693,943, dated February 25, 1902.

Application filed April 23, 1901. Serial No. 57,072. (No model.)

To all whom it may concern:

Be it known that I, WALTER J. BELL, a citizen of the United States, residing at No. 1046 West Thirty-seventh street, in the city of Los Angeles, county of Los Angeles, State of California, have invented a new and useful Improvement in Wings and Propellers for Flying-Machines and Machines for Aerial Navigation, of which the following is a specification.

My invention relates to an improvement in said wings and propellers—to wit, a system of automatic check-valves or automatic air-shutters to be attached to a wing or propeller for use on a flying-machine or other machine for aerial navigation; and the objects of my invention are to enable the said wing or propeller to exert the maximum amount of pressure upon the air in propelling the machine and its burden upward and forward and in sustaining it in the air with a minimum amount of pressure on the backward strokes thereof. The automatic opening and closing of the said check-valves or air-shutters by the upward thrusts of the wing or propeller and by the reverse motion thereof enables the wing or propeller to exert the maximum amount of force in upward and forward propulsion—that is, when its strokes are made downward or backward—with a minimum reverse—that is, downward and backward pressure—when the wing or propeller makes the necessary motions after having made one propelling stroke in order to secure a proper position for another propelling stroke. I attain these objects by the mechanism illustrated in the accompanying drawings, in which—

Figure 1 represents a plan view of a wing or propeller fitted with a system of check-valves or air-shutters and supporting-net, and Fig. 2 represents a vertical section of the wing or propeller on line D D.

A represents the framework of the wing, which may be composed of bamboo or other material which will have the maximum strength and the minimum weight.

B represents the check-valves or air-shutters, which in the form of wing or propeller shown in Fig. 1 may each run lengthwise of the wing to the beginning of the curved portion or the tip thereof, the curved portion of

the wing being fitted with a suitable number of said shutters or check-valves, or said valves may be indefinitely multiplied upon the netting covering the entire surface of the wing. 55

The net E covers over the entire framework of the wing and is composed of linen or other suitable material with suitable mesh in order to reduce to a minimum the air resistance on the upward and backward thrusts when the wing is opened, as hereinafter described. There may be used a net with a very large mesh superimposed upon or interwoven with a net with a small mesh, which will give additional strength and support as a base for 65 the strips, as hereinafter described.

The valves or shutters consist of strips of paper, parchment, celluloid, vellum rubber, oiled linen, unvulcanized sheet-rubber, or other suitable material running on the under 70 side of the wing from the portion of the framework nearest the body or machine to which the wing is made fast at A', the end thereof, by means of pivots of aluminium or other suitable material.

X is the front side of the wing, and Y the rear of the wing.

The strips are fastened by being sewed or cemented their entire length on the front side, on the lines shown as C, to the net, the rear 80 side or opposite edge of each strip swinging loose or free, so that each strip will be pressed downward by the pressure of the air against it when the wing is on the upward thrust, as shown by the dotted lines B', Fig. 2, and when 85 the wing is on the downward thrust the pressure of the air against the strips closes them against the netting, so that the strips thus opening from and closing against the netting in the upward and downward thrusts of the 90 wing act like check-valves, and the free side of each strip overlapping the fastened edge of the next strip closes the whole wing on the downward thrust, making the passage of the air through it impossible, while on the upward thrust the valves instantly opening permit the free passage of the air through every part of the wing. 95

What I claim as my invention, and desire to secure by Letters Patent, is— 100

1. The combination of a frame comprised of side and end members and intermediate

bars, of a netting secured to and extending over the frame at the upper side thereof, and overlapping valves or shutters hinged to the under side of the frame and contacting in 5 their closing position with the netting.

2. The combination of a transversely-curved frame comprised of side and end members one of the end members being bowed to provide a curved tip, intermediate strength- 10 ening-bars, a netting secured to and extend-

ing over the frame at the upper side thereof, and a plurality of overlapping valves or shutters hinged at one side to the under side of the frame and adapted to close against the netting.
